UNITED STATES PATENT OFFICE.

BENJAMIN CARL MCCLURE, OF SCARSDALE, NEW YORK.

ROD-PACKING.

1,325,950.

Specification of Letters Patent. Patented Dec. 23, 1919.

Application filed May 13, 1919. Serial No. 296,783.

To all whom it may concern:

Be it known that I, BENJAMIN C. MCCLURE, a citizen of the United States of America, residing at Scarsdale, county of Westchester, 5 State of New York, have invented certain new and useful Improvements in Rod-Packings, of which the following is a specification.

My invention relates to piston rod packing such as is used in steam engines, pumps, air compressors and the like and is designed to improve the quality and cheapen the process of manufacture thereof. One of the best embodiments of my invention at present known to me is illustrated in the accompanying sheet of drawing in which—

Figure 1 is a cross section of a stuffing box with my invention applied therein, parts being broken away, and

20 Fig. 2 is a cross section of the packing on an enlarged scale.

Throughout the drawings like reference characters indicate like parts. 1, is the cylinder head through which the piston rod 4, reciprocates, 2, is the gland of the stuffing box formed on the cylinder head, which gland is forced down on the packing 5, by bolts 3, in the usual way.

The packing itself is composed of the outer 30 wrapping 6, and a core block 8. The outer wrapping is composed of any suitable fabric, such as asbestos cloth, the layers of which are preferably held together by a layer 7, of any suitable cement, such as rubber cement, which will retain its adhesive quality 35 under heat and moisture. The core block 8, is formed of layers of any absorbent fabric. Asbestos cloth may also serve for making the core block, though other fabric may 40 be substituted. A strip of rubber 9, may also be inserted as shown to give greater resiliency to the packing.

The packing is placed in the stuffing box in the position shown in Fig. 1, with the 45 layers of the core parallel to the axis of the piston rod so that the pressure of the gland 2, will tend to buckle the layers apart and spread the packing radially of the piston rod and stuffing box, completely filling the 50 same and continually maintaining a tight joint with the piston rod to prevent leakage of the fluid under pressure in the cylinder.

To secure this result in the highest degree 55 the layers of the core block 8, should not be permanently stuck together, but must be

free to separate when in position for use. On the other hand these layers must be held temporarily together by some inexpensive method during the process of manufacture, 60 that is until the wrapping 6, has been applied and secured in position. These conflicting conditions are both satisfied according to my present invention by saturating the sheet or sheets of fabric from which 65 the core block is to be formed with some liquid such as a solution of starch which will stiffen it when dried, folding the sheet or sheets while still damp and pliable, and finally drying them after folding, as by running the core block through calendering rolls. The core block will then hold its 70 shape while the wrapping 6, is applied and secured in position.

When put into use, however, the heat of 75 the stuffing box, if free from moisture, will render the starch so brittle that it will crack, or powder under the pressure of the gland and free the layers of the core from inter-adhesion. If, on the other hand, steam or 80 water penetrates the wrapping 6, and cementing septum 7, the starch will be softened thereby and thus caused to lose its adhesive power on the core layers. In either case the layers of the core block are, after 85 being put into use, soon freed from inter-adhesion so that they are free to separate and buckle radially of the stuffing box, and so hug the piston rod tightly, which is the end sought with all rod packing. This mode 90 of operation is the exact opposite of that of a folded core block the layers of which are stuck together with rubber cement which hardens and toughens under heat and age, or held together by other permanent un- 95 yielding fastening means, such as have heretofore generally been used.

The broad principle of the present invention is the use of a means for temporarily holding the layers of the core block in position during manufacture, which shall disintegrate or otherwise lose its holding power under the conditions existing when the packing is in use.

The particular method of securing the 105 result herein contemplated is the treatment of the core of the fabric with some solution which will stiffen it when dried, but which will become brittle and lose its adhesive power under high heat and pressure, when 110 dry, and also soften and lose its adhesive power under action of moisture.

Having described my invention, I claim:

1. A packing having a core formed of fabric in parallel layers treated so that said layers will temporarily hold their relative positions under the conditions of manufacture, but are capable of being freed from inter-adhesion under the conditions of use.

2. A piston rod packing having a core of fabric arranged in layers parallel to the axis of the piston and set with a starch-like material which will be reduced to powder by dry heat, then easily fractured under pressure and also freed from adhesive qualities by moisture.

15 3. The method of forming a core block for

rod packing which comprises saturating absorbent fabric with a starch-like fluid which stiffens on drying out, but is reduced to powder by extreme heat and is softened by moisture, shaping said material while damp and pliable to form the block, and then drying it in position.

4. The method of forming a rod packing which comprises saturating an absorbent fabric with a starch solution, folding it to 25 form a core block while damp and pliable, drying it in folded position and wrapping with a cemented covering of suitable fabric.

BENJAMIN CARL McCLURE.
